NAILING MACHINE

Filed July 28, 1937

6 Sheets-Sheet 1

<img alt="Technical drawing of a mechanical assembly, likely a press or stamping machine, showing various components and part numbers. The drawing includes a main frame, a central vertical column, and various mechanical linkages and guides. A large horizontal beam at the top is supported by a central vertical column. The assembly includes a flywheel at the bottom right, a motor, and various gears and shafts. Numerous part numbers are indicated throughout the drawing, such as 10, 140, 142, 143, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 4410, 4411, 4412, 4413, 4414, 4415, 4416, 4417, 4418, 4419, 4420, 4421, NAILING MACHINE

Herbert E. Twomley, Riverside, Calif., assignor
to Food Machinery Corporation, San Jose,
Calif., a corporation of Delaware

Application July 28, 1937, Serial No. 156,098

18 Claims. (Cl. 1—14)

This invention relates to nailing machines and particularly to novel means for the feeding of box material to the same.

In the manufacture of boxes, crates and the like and in lidding the same, nailing machines are provided in which box material must be fed into the machine for the manufacture or lidding of the box. In some cases this material is fed into the machine by hand and in others by automatic mechanism.

It is an object of this invention to provide a novel and efficient means for feeding box material into a nailing machine.

Nailing machines used for the manufacture of boxes, crates or the like are generally divided into two classifications, automatic and semi-automatic. The first of these manufactures the box without requiring any manual manipulation of the work while the assembling of the box is going on. The semi-automatic type of machine is that in which it is necessary for the operator to manipulate the work to some degree at least during the manufacture of the box. In many of the latter types of machines it is necessary to feed the box material into the machine entirely by hand. This necessity considerably slows up the manufacture of boxes with the semi-automatic type machine.

It is another object of my invention to provide a semi-automatic nailing machine for the manufacture of crates, boxes or the like in which the box material forming the sides and bottom of the box is automatically fed into the machine.

It is a further object of this invention to provide such a nailing machine in which the box material is fed into the machine in such a manner as to allow ample room for the manipulation of the partly completed work by the operator to properly position this in the machine for the performance of the next nailing operation.

It is yet another object of my invention to provide in a nailing machine a means for automatically feeding box material into the machine to form the sides and bottom of the box where the bottom of the box is formed of a different number of separate pieces of box material than the sides thereof.

The manner of accomplishing the foregoing objects as well as further objects and advantages will be made manifest in the following description taken in connection with the accompanying drawings in which:

Fig. 1 is a front elevational view of a preferred embodiment of my invention.

Fig. 2 is a side elevation taken in the direction of arrow 2 in Fig. 1.

Fig. 3 is a fragmentary sectional view taken on the line 3—3 of Fig. 2.

Fig. 4 is a fragmentary operation view taken on the line 4—4 of Fig. 3.

Fig. 5 is an enlarged fragmentary sectional view taken on line 5—5 of Fig. 1 with the various parts of the machine at rest.

Fig. 6 is a view similar to Fig. 5 and illustrating the machine in the middle of a nail driving stroke.

Fig. 7 is a view similar to Fig. 6 and illustrates the machine at the completion of a nail driving stroke and in the midst of a work expelling and slat feeding movement of the slat feeding mechanism.

Fig. 8 is an enlarged horizontal sectional view taken on line 8—8 of Figs. 1 and 2.

Fig. 9 is a fragmentary detailed sectional view taken on the line 9—9 of Fig. 8.

Referring specifically to the drawings, the preferred embodiment of my invention illustrated therein comprises a nailing machine 10 which includes a frame 11, a power mechanism 12, a nail- 25 ing mechanism 13 and a slat feed mechanism 14.

The frame 11

The frame 11 includes a base 18 having secured thereon four standards or upright members 19 which are tied together at their upper ends by head castings 20 and a cross bar 21.

Mounted rigidly on the frame base 18, and provided for various purposes which will be made clear hereinafter, are main crank shaft bearings 35 25 and 26, countershaft bearings 27 and 28, slat feed mechanism power shaft bearings 29 and 30 and nail hopper counter shaft bearing 31. Adjacent to and above the bearing 31 is provided a nail hopper crank bearing 32. Also provided on base 18 is an idler bearing 33 and a motor foundation 34. The base 18 also has pedal shaft bearings 35. Mounted on and extending upwardly from each of the bearings 28 is a lever base bearing 36. The base 18 also provides a pair of clutch 45 release arm shaft bearings 37 and 38. (See Figs. 1 and 5.)

Power mechanism 12

This mechanism includes an electric motor 40 fixed upon the foundation 34, a crank shaft 41 journaled in the bearings 25 and 26, a counter shaft 42 journaled in the bearings 27 and 28, a slat feeding mechanism drive shaft 43 journaled in the bearings 29 and 30, a nail hopper counter 55

shaft 44 which is journalled in bearing 31 and a nail hopper operating crank shaft 45 which is journalled in bearing 32. Journalled in the foot pedal shaft bearings 35 is a foot pedal shaft 46 while a clutch release arm shaft 47 is journalled in bearings 37 and 38. (See Figs. 1 and 5.)

Fixed on opposite ends of shaft 41 are nail driving cranks 50. Between these cranks and the bearings 25 and 26 are provided nail chuck and slat feed mechanism lifting cams 51. Also fixed on shaft 41 just inwards from bearing 26 is a master gear 52 and inwards from this a clutch operating cam 53 and inwards from this a clutch normalizing arm 54. (See Fig. 3.)

Countershaft 42 has mounted thereon a pinion gear 60 which meshes with the master gear 52, a pinion gear 61, a clutch 62, a clutch operating ring 63 and a brake mechanism 64.

The slat feed mechanism operating shaft 43 (Figs. 4 and 5) has mounted thereon a clutch 65 having on the periphery thereof a ring gear 66 which meshes with the pinion gear 61 on shaft 42. The shaft 43 also has upon it a pinion 67 and a drive sprocket 68.

On the shaft 44 is mounted a gear 72 which meshes with the pinion gear 67 on the shaft 43 and also has a pinion 73 which meshes with a gear 74 provided on the nail hopper crank shaft 45. On the outer end of said crank shaft is provided a crank 75.

Provided on foot pedal shaft 46 is a foot pedal 76 and a clutch arm 77 which operatively engages the clutch operating ring 63 of the clutch 62. Fixed on the shaft 47 is an arm 78 having a cam 35 follower roller 79 thereon, the latter being in alignment with the cam 53. Also fixed on shaft 47 is a clutch release arm 80, (see Figs. 1 and 5) the upper end of this arm lying in the path of rotation of a clutch control finger 81, the latter 40 being provided on the clutch 65 and adapted to control the latter so that when positioned as shown in Fig. 5 this finger throws clutch 65 out but when released from contact with the arm 80 it is yieldably extended into radial position as 45 shown in Fig. 7 thereby throwing into engagement the clutch 65 and connecting the gear 66 with the shaft 43. The arm 78 is yieldably supported by a spring 85 in the position in which it is shown in Fig. 5.

Pivotedly mounted on the idler bearing 83 is an idler arm 86 having an idler roller 87 which is pulled inwardly in radial alignment with the sprocket 68 by a spring 88 for a purpose which will be made clear hereinafter.

The motor 40 has a pinion sprocket 93 which connects through a chain 91 with a ring sprocket 92 provided on the shell of the clutch 62 and through which this clutch is continuously driven by the motor 40.

60 The nailing mechanism 13

Included in this mechanism are four cross head slide track plates 95 which are secured upon inner faces of the corner posts 19 of the machine. (See Figs. 1, 2 and 8.)

Fixed upon the lower ends of the plates 95 are anvil bases 96 upon which anvils 97 are pivotally mounted on shafts 98 and yieldably urged by springs 99 into positions for supporting side or bottom rails 100 of crate heads H when the latter are inserted into the machine 10. Provided on brackets 105 and 106 extending rearwardly from the anvil bases 96 are a shifting shaft 107 and a fixed shaft 108. Rigidly fixed on the bracket 70 75 105 and extending along the left hand side of the

machine above the anvils 97 adjacent thereto is a crate head stop 109. In a similar position on the right hand side of the machine is a crate head end stop 110, the latter, however, not being fixed rigidly on the frame of the machine but being mounted on the shafts 107 and 108 so as to be fixed on the shaft 107 and slideable relative to the shaft 108. Also mounted on the shafts 107 and 108 so as to snugly fit these are a pair of slide blocks 113 and 114, the first of which is 10 fixed to the shaft 107 and freely slideable on the shaft 108, and the latter of which is fixed to the shaft 108 and freely slideable on the shaft 107. Mounted on the block 113 is a spring pressed crate head flusher 115, while mounted on the block 114 is a similar spring pressed crate head flusher 116.

Disposed between the bracket 105 and the block 113 is a compression spring 117. The shaft 107 extends through the bracket 105 and has 20 fixed to the left hand extremity thereof a pair of expansion members 118 and 119, the first of these being rigidly fixed to the shaft 107 on its extremity, while the latter is disposed between the member 118 and the bracket 105. (See Fig. 25 8.) These two expansion members have complementary bevelled-tooth faces which function when the member 119 is rotated relative to the member 118, to shift the shaft 107 and parts affixed thereto in a leftward direction as these 30 are viewed in Fig. 8. The operation of the expansion members 118 and 119 in this manner is accomplished by an arm 120 which is provided on the member 119 and which is actuated in a manner which will be made clear hereinafter. 35

The nailing mechanism also includes a pair of nail chuck crossheads 125 which are slidably guided vertically, front and rear portions of these crossheads having a sliding fit with the front edges of the front slide plates 95 and the rear edges of the rear slide plates 95. Each of the crossheads 125 has provided thereupon four groups 126, 127, 128 and 129 of nail chucks 130, these being in alignment and disposed in the order in which they are enumerated from the front towards the rear of the machine. (See Figs. 1, 5, 6 and 7.) The nail chucks 130 are adapted to receive nails, each chuck receiving one nail at a time, and hold these nails in position for driving downwardly into work supported on 50 these anvils 97 when said work is positioned on these anvils against the crate head stop bars 109 and 110.

Disposed between and slidably engaging the adjacent edges of the slide bars 95 on each side 55 of the machine is a nail driver crosshead 135. These crossheads have nail drivers 136 which extend downwardly into the nail chucks 130 and these drivers are caused, by relative vertical movement between the crossheads 135 and 125, 60 to expel nails from the nail chucks 130 in the performing of a nailing operation.

Pivottally mounted on the head castings 20 of the machine 10 are nail hoppers 140 and 141 which are linked together by tie rod 142 so that 65 rocking of the hopper 141 results in a corresponding operation of the nail hopper 140. The nail hoppers 140 and 141 are associated with nail feed mechanisms 143 which cooperate with the hoppers 140 and 141, in a manner well known in 70 the art, to feed nails to the nail chucks 130. The mechanisms 143 feed nails selectively to the chucks 130 as will be described hereinafter.

The various components of the nailing mechanism 13 described hereinabove are provided with 75

means for their actuation as follows: Connecting the cranks 50 with the nail driver crossheads 135 are pitmans 150, these including yieldable spring compensators 151. The pitman 150 on the left-hand side of the machine 10 has a bolt 152 which lies in a slot 153 formed in the forward end of the arm 120 so that this arm is swung downwardly and upwardly with each reciprocation of this pitman 150, the effect of this being made clear hereinafter.

Disposed on each side of the machine 10 and having their rear ends pivotally mounted in bearings 36 are cam follower arms 156 having pins 157 provided at their ends upon which are mounted rollers 158 which rest upon and follow the surfaces of the cams 51 as the shaft 41 rotates. Also mounted on the pins 157 are links 160 which extend upwardly into the machine and have their upper ends pivotally connected to the chuck crossheads 125 at 125'. (See Figs. 2, 6, 8 and 9.)

Provided on the upper ends of the standards 19 at the right of the machine 10 are bearings 161, in which is journalled a shaft 162, carrying an arm 163 which is connected by a link 164 to the nail hopper 141 and by pitman 165 to crank 75. (See Figs. 1 and 2.)

Provided on the frame 11 in alignment with heads H when the latter are inserted in the machine are work stops 170 and 171.

Slat feed mechanism 14

Secured to the inner faces of upper portions of the slide bars 95 of the machine 10 (see Figs. 2 and 9) are brackets 175 which are integral with side walls 176 of a slat magazine 177. The magazine 177 also has vertical flanges 178 extending inwardly from the front edges of the side walls 176 and a pair of angle irons 180 adjustably secured thereto by bolts 181 extending through slots 182 in the side walls. The flanges 178 and angle irons 180 form front and rear walls, respectively, for the magazine 177. Secured at its opposite ends to lower portions of the flanges 178 is a cross bar 183 and likewise connecting lower portions of the side walls 176 is a rear cross bar 184. Secured to the middle of the cross bar 183 and extending downwardly a short distance therefrom and then horizontally forward is a friction shoe 185, the forward end of which is yieldably held downwardly by a rod 186, the latter extending upwardly through the bar 21 and having a coil spring 187 which biases it downwardly and nuts 188 by which the vertical position of the front end of the shoe 185 may be adjusted.

Also provided on the cross bar 183, as shown in Fig. 9, and adjustable vertically thereon are gauge plates 190 which retain in the magazine 177 all of the slats but the lowermost slat. Provided on the cross bar 184 and extending downwardly and forwardly beneath the magazine 177 are slat supporting rods 192. (See Figs. 6 and 9.)

Secured to the bottoms of the side plates 176 of the magazine 177 are conveyor guide brackets 193 having vertical slots 194 therein.

The slat feed mechanism also includes a slat conveyor 200 which has a pair of triangular frames 201 providing at their corners bearings 202, 203 and 204 in which are journalled respectively shafts 205, 206 and 207. Each of these shafts has fixed thereto a pair of sprockets 208 which lie just outside the frames 201 and about which are trained endless chains 210. Provided

on these chains are three sets 211, 212 and 213 of dogs 214, the foremost dogs of these sets being equally spaced about the chains 210.

Opposite ends of the shaft 205 extend laterally into and are guided by the slots 194 of brackets 193. The opposite ends of the shaft 207 also extend laterally and are pivotally connected to rear ends of lever bars 220, the front ends of these bars being pivoted at 221 on the front pair of corner posts 19. (See Figs. 5, 6 and 7.) Pivotally connected at their opposite ends to arms 156 and to the levers 220 are links 222. Fixed on one end of the shaft 207 is a sprocket 225 which is disposed above and in alignment with the slat conveyor drive sprocket 68 (see Figs. 3 and 4). Encircling the sprockets 68 and 225 is a slat conveyor drive chain 226, this chain also being constantly engaged and maintained in taut condition by the idler roller 87.

20

Operation

The principal operating views are Figs. 5, 6 and 7, the first of which illustrates the machine 10 at rest with the parts disposed as at the beginning of the manufacture of a crate. It is to be noted that three slats S are resting on the chains 210 with the slat conveyor 200 disposed upwardly owing to the fact that the cam follower rollers 158 are resting on the high portions of the cams 51. These slats S are disposed just in front of dogs 214 of the group 211 thereof. It is also to be noted that these slats are snugly engaged by the dogs 214 just to the rear thereof, this being due to the frictional engagement of the shoe 185 with the upper surfaces of these slats S as the latter were being fed forwardly by the conveyor 200 into the positions in which they are shown at rest in Fig. 5. It is further to be noted that these slats as thus disposed are located at a considerable distance above the nailings anvils 97. Attention is also called to the chucks 130 being spaced upwardly from the slats S disposed therebeneath and to the fact that substantial portions of the nail drivers 136 are withdrawn upwardly from the chucks.

The operator now positions a pair of crate heads H in the machine by pushing these rearwardly between the anvils 97 and the crate head flushers 115 and 116, with short edges of these heads horizontal, with the upwardly disposed rails 100 extending laterally over the anvils 97, and with the heads extending rearwardly in contact with stops 170. The anvils 97 of course yield outwardly about the shafts 98 due to the curved surfaces 97' as the heads H are being pushed into the machine and then rock back again into position beneath the rails 100 disposed thereover. (See Fig. 9.) Each of the heads of course is provided with a rail 100 along each of its sides and bottom so that no matter which side of the heads or the bottom thereof is disposed upwardly this has a rail 100 which is adapted to extend over the adjacent anvil 97 as shown in Fig. 9.

It is to be understood that at this time the motor 40 is electrically energized to cause the constant rotation of the clutch 62 through the chain 91 which connects the ring gear 92 with the motor pinion 90. As the pinion 61 is fixed to the clutch 62 and continually rotates therewith, the clutch 65 is also caused to rotate continuously although at a lower rate of speed than clutch 62. The shafts 41, 42 and 43 are of course stationary so long as the clutches 62 and 65 remain disengaged.

75

Having inserted the heads H, as above indicated, the operator steps on the pedal 76 and immediately removes his foot therefrom. This swings the arm 77 so as to shift the clutch control collar 63 inwardly to engage the clutch 62 and start the shaft 42 rotating with said clutch. This transmits rotation through the pinion 69 and gear 52 to the crank shaft 41 and causes exactly one revolution of this shaft, at the completion of which, arm 54 on the shaft 41 engages the clutch collar 63 and throws out the clutch 62. The disengagement of this clutch automatically operates the brake 64 in a manner well known in the art to immediately stop rotation 15 of the shaft 42 and the shaft 41 connected therewith.

It might be here pointed out that the making of a crate or the like in the machine 10 involves a succession of three operations each of which is 20 initiated by the operator depressing the foot pedal 76 and by the functions of the machine which automatically result therefrom. In the first of these operations a side comprising three separate slats S is nailed to corresponding edges 25 of the two crate heads H. The second of these operations nails a bottom to the crate heads which bottom comprises four separate slats. The third operation nails a second side to the crate heads, which side comprises three separate slats. 30 The nail feed mechanisms 143 operate in a manner well known in the art to feed nails selectively to the groups 126, 127, 128 and 129 of nail chucks 130 so that when the machine is at rest prior to commencing each of the operations 35 for nailing a side on to the crate, nails are contained only in the chucks 130 in the groups 126, 127 and 128 thereof, and so that just prior to the operation in which a bottom is nailed to the crate, nails are provided in all of the chucks 130. The 40 reason for this is that the slat conveyor 200 prior to each of the side nailing operations feeds three slats S into position just beneath the groups of chucks 126, 127 and 128, as shown in Fig. 5, and in the nailing operation which immediately follows nails are driven from the chucks 130 in these 45 groups through these three slats and into the crate heads H disposed therebeneath.

Just before the operation of machine 10 in which a four slat bottom is applied to the crate, 50 however, the slat feed mechanism 200 feeds four slats S into position to be nailed to the crate heads, the foremost three of these slats being then located exactly as the three slats S shown in Fig. 5 and the fourth slat being located with its ends directly beneath the groups 129 of chucks 130. These four slats are, of course, fed into place by the dogs 214 of the group 212 thereof 55 provided on the chains 210. It is thus seen that when four slats are to be nailed to the crate heads in a given nailing operation the groups 129 of chucks 130 are previously supplied with nails by the nail feed mechanism 143 but when only three slats are to be nailed to the crate head, only the groups 126, 127 and 128 of chucks 130 have previously been furnished with nails 60 by the nail feed mechanisms.

Referring now to the initial single revolution of the shaft 41, which was effected in the manner described hereinabove, it is noted that this performs the following functions. Being fixed to the shaft, the cams 51 and 53 rotate therewith in the direction of the arrow 230 in Fig. 6, causing the rollers 158 to ride downwardly from the upper cam surfaces of the cams 51 onto the lower cam 70 surfaces thereof thus lowering the slat conveyor 75

200 and the nail chuck crossheads 125. The conveyor 200 and crossheads 125 are shown in their downwardmost position in Fig. 6 where it is seen that the conveyor 200 has deposited the three slats S carried thereby onto the upper faces of the rails 100 of the crate heads H which rest upon the anvils 97; and the groups 126, 127 and 128 of nail chucks 130 are brought to rest upon opposite ends of these slats S.

As the ends of the three slats S come to rest 10 on the crate heads with the designated groups of nail chucks resting on top of the slat ends, the nail driver crossheads 135 are drawn downwardly by the cranks 50 and pitmans 150 causing the individual nail drivers 136 to slide downwardly 15 in the nail chucks 130 whereby the nails previously delivered to those groups of these chucks which rest on the slats S are driven downwardly through these slats into the crate heads, the consumption of the nail driving movement being ill- 20 illustrated in Fig. 6.

During the latter half of the initial single revolution of the shaft 41, the results of which are here being described, the nail driver crossheads 135, the chuck crossheads 125 and the slat conveyor 200 are all returned to their uppermost positions in which they are shown in Fig. 5. Just as the shaft 41 is completing this single revolution, the cam 53 thereon engages the cam follower roller 79 on the arm 78 and depresses this arm 30 to rock the shaft 47 and swing the arm 80 out from beneath the clutch control finger 81, thereby causing the clutch 65 to be thrown into engagement.

This commences the single revolution of the 35 shaft 43 which, through the drive sprocket 68 and the chain 226, rotates the shaft 204 of the conveyor 200 and causes the chains 210 to travel about the sprockets 208 of the conveyor. This moves the dogs 214 of the group 211 against those 40 three slats S which have just been nailed to the crate heads H and expel the partially completed work from the machine in the manner shown in Fig. 7. At the same time the group 212 of dogs 214, of which there are four on each of the chains 45 210, comes successively into engagement with slats S in the bottom of magazine 177 so as to feed a group of four slats from this magazine whereby, at termination of the single revolution of the shaft 43 which causes the traveling of the 50 chains 210, the first three of these four slats will be disposed exactly as the three slats S shown in Fig. 5, while the fourth slat of the new group of four will be disposed with its ends directly beneath the groups 129 of nail chucks 130. 55

As soon as the unfinished work comprising 60 crate heads H with the first side of three slats nailed thereto has been ejected from the machine 10 by the slat conveyor 200, as shown in Fig. 7, the operator seizes the unfinished work in his hands and turns it 90 degrees so that the slats of the first side are disposed towards him and the long edges of the crate heads are disposed horizontally. Whereupon he pushes the crate heads H back into the machine against stops 65 171 with the upwardly disposed rails 100 of the heads resting on the nailing anvils 97.

When the operator has completed this repositioning of the work and the slat feed conveyor 70 200 has finished feeding four slats into position as hereinabove described the operator again steps on the pedal 76. This results in the lowering of the slat conveyor 200, the nail chuck crossheads 125 and the nail driver crossheads 135 to de- 75

posit the four bottom slats onto the crate heads and nail these slats to the heads.

At the conclusion of the bottom nailing operation the unfinished work is again ejected by the automatic traveling of the chains 210 as the latter move to feed three new slats into place for applying the second side to the crate. The unfinished work when thus ejected into the hands of the operator is again rotated by him 90 degrees and reinserted into the machine against the stops 170 in position for receiving the second side. The operator then steps on the pedal 76 a third time, which results, in the same manner as above described, in the nailing of the second side of three slats onto the crate heads H, thus completing the crate, which is ejected at the completion of these nailing operations by the chains 210 moving to feed three new slats S into place, as shown in Fig. 5 in readiness for the starting of the manufacture of another crate.

As the pitmans 150 move downwardly during each nail driving operation the bolt 152 provided in the left-hand pitman 150 swings the arm 120 downwardly, and rocks the hub 119 thereof relative to the member 118, causing a left-hand shifting of the shaft 107. This shifts the flusher 115 against the crate head H inserted in the left-hand side of the machine to hold this head flush against the head stop 109. At the same time this left-hand shifting of the shaft 107 carries with it the crate head stop 110 on the right-hand side of the machine so as to cause the stationary flusher 116 to press the right-hand crate head flush against the stop 110, this left-hand movement of the latter bringing the stops 109 and 110 into a precisely spaced relationship which by virtue of the crate heads now being forced thereagainst results in crates being manufactured having a definite predetermined length.

Upon the return upward of the bolt 152 with the pitman 150 to which it is attached the arm 120 and hub member 119 swing backward to the positions in which they are shown in Fig. 8, thus shifting the shaft 107 to the right and releasing the crate heads from compression between the head stops 109 and 110 and the flushers 115 and 116.

With each revolution of the shaft 43 the gear 72 is rotated by virtue of its meshing with pinion 67 and this rotates the shaft 45 through the gears 73 and 74 and causes the crank 75 to reciprocate the pitman 165 which, through the lever 163 and link 164 and tie rod 142, accomplishes the rocking of the nail hoppers 140 and 141 to keep a constant supply of nails accessible to the nail feed mechanisms 143.

I hereby claim:

1. In a nailing machine the combination of: nailing mechanism; anvil means for supporting a pair of box heads in spaced relation in each of three positions to permit said nailing mechanism to secure thereto consecutively a first side, a bottom and a second side; means for feeding a series of independent slats into the proper places to be nailed to said heads, with the latter in each of the aforesaid three positions, to form said sides and bottom in said heads; and means automatically controlled by the completion of each nailing operation performed by said nailing mechanism, to cause said slat feed means to feed slats into their proper places for assembly on said heads in the next succeeding nailing operation.

2. A combination as in claim 1 in which said

slat feeding means expels the work from its nailing position in the machine immediately following each nailing operation.

3. In a semi-automatic nailing machine the combination of: nailing mechanism; anvil means for supporting a pair of box heads in spaced relation successively in three positions to permit the operation of said nailing mechanism in securing to said heads consecutively a first side, a bottom and a second side; means for feeding box material into proper place relative to said box heads when the latter are in each of the aforesaid three positions in order for said box material to be nailed to said box heads to form said sides and bottom; and means automatically operable in timely relation with said nailing mechanism to cause said box heads to be expelled from each of their positions as aforesaid on said anvil means following the nailing of a side or bottom to said heads while the latter are so positioned, and to feed box material into proper place relative to said nailing mechanism and anvil means to be nailed to said box heads when the operator has placed the latter in the next of said three positions to form the next of said sides or bottom to be applied to said heads.

4. In a semi-automatic nailing machine the combination of: nailing mechanism; anvil means for supporting a pair of box heads in position beneath said nailing mechanism to permit box material to be nailed to three pairs of edges of said heads to form the sides and bottom of a box; and endless chain means operable in timely relation with said nailing mechanism to expel said heads from nailing position on said anvil means and to feed new box material into place to be nailed to said box heads when the latter are repositioned on said anvil means by the operator.

5. In a nailing machine the combination of: nailing mechanism; anvil means for supporting a pair of box heads in spaced relation in each of three positions to permit said nailing mechanism to secure thereto consecutively a first side, a bottom and a second side; an endless chain conveyor for feeding a series of independent slats into the proper places to be nailed to said heads, with the latter in each of the aforesaid three positions, to form said sides and bottom on said heads; and means for operating said endless chain conveyor to cause it to perform its functions aforesaid in timely relation with said nailing mechanism.

6. In a nailing machine the combination of: nailing mechanism anvil means for supporting a pair of box heads in spaced relation in each of three positions to permit said nailing mechanism to secure thereto consecutively a first side, a bottom and a second side; an endless chain conveyor for feeding a series of independent slats into the proper places to be nailed to said heads, with the latter in each of the aforesaid three positions, to form said sides and bottom on said heads, a plurality of said slats being fed by said conveyor for the formation of each of said sides and bottom, a different number of said slats being fed for the formation of said bottom than are fed for the formation of each of said sides; and means for operating said conveyor to cause the same to perform its functions aforesaid in timely relation with the operation of said nailing mechanism.

7. A combination as in claim 4 in which said new box material when first fed into said machine by said endless chain means is disposed a substantial distance above said anvil means to

allow ample room for the operator to manipulate the box heads into their new positions on said anvil means.

8. A combination as in claim 4 in which said new box material when first fed into said machine by said endless chain means is disposed a substantial distance above said anvil means to allow ample room for the operator to manipulate the box heads into their new positions on said anvil means; and means for automatically lowering said endless chain means to bring said new box material into contact with said box heads prior to the functioning of said nailing mechanism to nail said box material to said box heads.
9. In a nailing machine the combination of: a nailing mechanism; anvil means for supporting a pair of box heads in spaced relation in each of three positions to permit said nailing mechanism to secure thereto consecutively a first side, a bottom, and a second side; endless chain means for feeding box material into place between said nailing mechanism and said box heads to form one of said sides or bottom; and means for shifting said endless chain means vertically in timed relation with the operation of said nailing mechanism to prevent said new box material, when fed into said machine, from interfering with the change of said box heads from one of the aforesaid positions thereof to a subsequent one of said positions.

10. In a nailing machine the combination of: a nailing mechanism; anvil means for supporting a pair of box heads in spaced relation in each of three positions to permit said nailing mechanism to secure thereto consecutively a first side, a bottom, and a second side; endless chain means for feeding box material into place between said nailing mechanism and said box heads to form one of said sides or bottom; and means for reciprocating said endless chain means vertically in timely relation with the operation of said nailing mechanism to prevent said new box material, when fed into said machine, from interfering with the change of said box heads from one of the aforesaid positions thereof to a subsequent one of said positions and to cause said endless chain means to place said new box material in contact with said box heads prior to the nailing of said new box material to said box heads.

11. In a nailing machine the combination of: a nailing mechanism; a slat magazine; an endless chain conveyor; dogs on said conveyor for stripping slats from said magazine; anvils for supporting box heads in spaced relation beneath said nailing mechanism; and means for actuating said conveyor in timely relation with said nailing mechanism to strip slats from said magazine and deliver said slats into proper positions to be nailed to heads resting on said anvils.

12. In a nailing machine the combination of: a nailing mechanism; a slat magazine; an endless chain conveyor; dogs on said conveyor for stripping slats from said magazine; anvils for supporting box heads in spaced relation beneath said nailing mechanism; means for actuating said conveyor to strip slats from said magazine and deliver said slats into proper positions to be nailed to heads resting on said anvils; and means for engaging said slats on said conveyor and restraining said slats against disarrangement until just before the nailing operation takes place in which said nailing mechanism nails said slats to said heads.

13. In a nailing machine the combination of: a slat magazine; an endless chain conveyor; dogs

on said conveyor for stripping slats from said magazine and conveying slats to a nailing position; anvil means for supporting spaced box heads beneath said position; means causing relative vertical movement between said anvil means and said conveyor to cause said slats to be deposited on box heads supported on said anvil means; and a nailing mechanism for nailing said slats to said box heads when said slats are thus deposited on said box heads.

14. In a nailing machine the combination of: a slat magazine; an endless chain conveyor; dogs on said conveyor for stripping slats from said magazine and conveying slats to a nailing position; anvil means for supporting spaced box heads beneath said position; means causing relative vertical movement between said anvil means and said conveyor to cause said slats to be deposited on box heads supported on said anvil means; a nailing mechanism for nailing said slats to said box heads when said slats are thus deposited on said box heads; and means for causing said conveyor to stop feeding said slats when the latter arrive in said nailing position and causing said conveyor to start up again after said nailing operation so as to expel the work from nailing position.

15. In a fastener inserting machine, the combination of: a fastener inserting mechanism; anvil means for supporting work including end members and transverse members, while being operated on by said mechanism; a magazine for holding said transverse members; an endless chain conveyor; dogs on said conveyor for stripping transverse members from said magazine; and means for actuating said conveyor in timely relation with said fastener inserting mechanism to strip transverse members from said magazine and deliver said members into proper position to be fastened to said end members by said mechanism while the work is resting on said anvil means.

16. In a fastener inserting machine, the combination of: a fastener inserting mechanism; anvil means for supporting work including end members and transverse members, while being operated on by said mechanism; a magazine for holding said transverse members; an endless chain conveyor; dogs on said conveyor for stripping transverse members from said magazine; and means for actuating said conveyor in timely relation with said fastener inserting mechanism to strip transverse members from said magazine and deliver said members into proper position to be fastened to said end members by said mechanism while the work is resting on said anvil means, said chain conveyor operating upon the conclusion of the operation of said mechanism on said work, to expel said work from said machine.

17. In a fastener inserting machine, the combination of: a fastener inserting mechanism; anvil means for supporting work including end members and transverse members, while being operated on by said mechanism; a magazine for holding said transverse members; an endless chain conveyor; dogs on said conveyor for stripping transverse members from said magazine; means for actuating said conveyor in timely relation with said fastener inserting mechanism to strip transverse members from said magazine and deliver said members into proper position to be fastened to said end members by said mechanism while the work is resting on said anvil means; and means producing relative vertical

movement between said chain conveyor and said anvil means, said movement locating said work in operative relation with said anvil means at the beginning of the operation of said fastener inserting mechanism.

18. In a fastener inserting machine, the combination of: a fastener inserting mechanism; anvil means for supporting work including end members and transverse members, while being operated on by said mechanism; a magazine for holding said transverse members; an endless chain conveyor; dogs on said conveyor for stripping transverse members from said magazine; means for actuating said conveyor in timely relation with said fastener inserting mechanism to strip transverse members from said magazine

and deliver said members into proper position to be fastened to said end members by said mechanism while the work is resting on said anvil means; and means producing relative vertical movement between said chain conveyor and said anvil means, said movement locating said work in operative relation with said anvil means at the beginning of the operation of said fastener inserting mechanism, said relative vertical movement also removing said work from engagement with said anvil means at the completion of the operation of said fastener inserting mechanism, said chain conveyor then automatically expelling the work from operative relation with said mechanism.

HERBERT E. TWOMLEY.
